UNITED STATES PATENT OFFICE.

WILLIAM C. CODMAN, OF PROVIDENCE, RHODE ISLAND, ASSIGNOR TO DOW, JONES & CO., OF NEW YORK, N. Y.

DESIGN FOR A MEMBER FOR PAPER-FILE CLAMPS.

SPECIFICATION forming part of Design No. 36,643, dated November 24, 1903.

Application filed October 7, 1903. Serial No. 176,156. Term of patent 14 years.

To all whom it may concern:

Be it known that I, WILLIAM C. CODMAN, a subject of the King of Great Britain, residing at Providence, in the county of Providence and State of Rhode Island, have invented a new, original, and ornamental Design for a Member of a Paper-File Clamp, reference being had to the accompanying drawing.

The figure in the drawing represents an obverse view of a member of a paper-file clamp embodying my design.

What I claim as new, and desire to secure by Letters Patent, is—

The ornamental design for a member of a paper-file clamp, as shown.

In testimony whereof I have signed my name to this specification in the presence of two subscribing witnesses.

WILLIAM C. CODMAN.
